A model toy includes: a main body including a plate portion; a first figure body provided on the plate portion; and a second figure body provided on the plate portion so as to be arranged in a state where the second figure body is close to the first figure body along an arrangement direction in which the first figure body and the second figure body are arranged. The first figure body engages the plate portion immovably. The second figure body engages the plate portion movably to allow the second body to move in a direction in which the second figure body is separated from the first figure body along the arrangement direction.

MODEL TOY AND COOKING TOY

CROSS-REFERENCE TO RELATED APPLICATIONS

This application is based on and claims priority under 35 USC 119 from Japanese Patent Application No. 2022-172179 filed on Oct. 27, 2022, the contents of which are incorporated herein by reference.

TECHNICAL FIELD

The present disclosure relates to a model toy and a cooking toy.

BACKGROUND ART

In the related art, model toys imitating kitchenware have been provided. For example, JP2018-164492A discloses, as a toy set, an imitation oven in which an intermediate material obtained by mixing a base material and an expansion agent can be input. When the intermediate material produced as a dough of imitation bread is input in the imitation oven, the intermediate material rises with a thickness of about 1.2 times after 20 minutes. Then, a baked color is added by applying an oily agent to the imitation bread after drying, as disclosed.

SUMMARY OF INVENTION

In the above-described model toy disclosed in JP2018-164492A, however, a time is required to obtain the imitation bread from the input of the dough, and thus a pleasure imitating a state change before and after cooking cannot be simply enjoyed.

An object of the present disclosure is to provide a model toy and a cooking toy for simply enjoying a pleasure imitating a state change before and after cooking.

The present disclosure provides a model toy including: a main body including a plate portion; a first figure body provided on the plate portion; and a second figure body provided on the plate portion so as to be arranged in a state where the second figure body is close to the first figure body along an arrangement direction in which the first figure body and the second figure body are arranged, in which: the first figure body engages the plate portion immovably; and the second figure body engages the plate portion movably to allow the second body to move in a direction in which the second figure body is separated from the first figure body along the arrangement direction.

The present disclosure provides a cooking toy including: a main body including a plate portion; a first figure body provided on the plate portion and defining a part of a cooking object; a second figure body provided on the plate portion so as to be arranged in a state where the second figure body is close to the first figure body along an arrangement direction in which the first figure body and the second figure body are arranged, the second figure body defining a rest part of the cooking object to define a whole shape of the cooking object when the second figure body is continuous with the first figure body; and a third figure body imitating a shape of a cutter configured to cut the cooking object, in which: the first figure body engages the plate portion immovably; and the second figure body engages the plate portion movably to allow the second figure body to move in a direction in which the second figure body is separated from the first figure body along the arrangement

2

direction when a side of the second figure body facing the first figure body is pressed by the third figure body.

According to the present disclosure, it is possible to provide a model toy and a cooking toy for simply enjoying a pleasure imitating a state change before and after cooking.

BRIEF DESCRIPTION OF DRAWINGS

The present disclosure will be described in detail based on 10 the following without being limited thereto, wherein:

FIG. 1 is a perspective view illustrating an overall kitchen toy according to an embodiment of the present disclosure;

FIG. 2 is a perspective view illustrating the kitchen toy when viewed from the upper side according to the embodiment of the present disclosure;

FIG. 3 is a perspective view illustrating a right-side carrot model and a left-side carrot model when viewed from the lower side;

FIG. 4A is a perspective view illustrating the vicinity of 20 a chopping board and a kitchen knife model in a state where the left-side carrot model is close to the right-side carrot model;

FIG. 4B is a perspective view illustrating the vicinity of the chopping board and the kitchen knife model in a state 25 where the left-side carrot model is away from the right-side carrot model;

FIG. 5A is a top view illustrating the vicinity of the chopping board in the state where the left-side carrot model is close to the right-side carrot model; and

FIG. 5B is a top view illustrating the vicinity of the 30 chopping board in the state where the left-side carrot model is away from the right-side carrot model.

DESCRIPTION OF EMBODIMENTS

An embodiment of the present disclosure will be described with reference to the drawings. As illustrated in FIG. 1, according to the embodiment of the present disclosure, a kitchen toy (a model toy or a cooking toy) 1 imitating 35 a kitchen will be described. The kitchen toy 1 is a toy with which meal time playing house can be done using a doll or the like. The kitchen toy 1 is formed in a substantially rectangular parallelepiped shape which is overall horizontally long and includes a main body 10 in which a sink stand 12 and a cooking table 14 are provided. A door 16 is provided below the sink stand 12. A drawer 17 and an accommodation space 18 are provided below the cooking table 14. Hereinafter, the door 16 side of the kitchen toy 1 is referred to as a front side and its opposite side is referred 40 to as a rear side. A drawer 17 side when the kitchen toy 1 is viewed from the front side is referred to as a right side and its opposite side is referred to as a left side for description.

As illustrated in FIG. 2, a chopping board (a plate portion) 20 with a slab shape is provided on the upper surface of the 45 cooking table 14. A right-side carrot model (first figure body) 31 that is a figure body imitating a portion from a stem part to the middle of a trunk part of a carrot model (cooking object) 30 imitating a carrot and a left-side carrot model (second figure body) 32 that is a figure body imitating a portion from the middle of the trunk part to a tip part of the 50 carrot model 30 are provided on the chopping board 20. The right-side carrot model 31 and the left-side carrot model 32 are arranged in parallel in the right and left directions on the chopping board 20 at a position at which portions imitating 55 the middle of the trunk part of the carrot model 30 are close to each other such that the right-side carrot model 31 is on the right side and the left-side carrot model 32 is on the left 60 65

side. Both the right-side carrot model 31 and the left-side carrot model 32 become close to each other and join to form the shape of the carrot model 30 as a whole.

In the kitchen toy 1, when a user puts down a kitchen knife model (third figure body) 40 (see FIGS. 4A and 4B) to a boundary B (see FIG. 3 or the like) between the right-side carrot model 31 and the left-side carrot model 32 from the upper side to the lower side in a state where the right-side carrot model 31 and the left-side carrot model 32 are close to each other, the left-side carrot model 32 moves to the left and a gap between the right-side carrot model 31 and the left-side carrot model 32 is opened. Accordingly, the user playing with the kitchen toy 1 feels a sense of cutting the carrot model 30 including the right-side carrot model 31 and the left-side carrot model 32 with the kitchen knife model 40. The kitchen toy 1 is a toy with which cooking can be enjoyed in an imitation manner as such. Hereinafter, a configuration of each member of the kitchen toy 1 will be described in detail.

As illustrated in FIGS. 1 and 2, the main body 10 is configured such that an external wall portion 10a forming the front surface, the rear surface, right and left side surfaces, and the lower surface, a top plate portion 10b forming the upper surface, and an upper wall portion 10c formed along the rear end edge of the upper surface are integrated. The inside of the external wall portion 10a is hollow. The door 16 provided on the front surface side of the external wall portion 10a is a hinged door which is a double wing door. A faucet 12a and a sink 12b are disposed in the sink stand 12 provided on the left side of the top plate portion 10b. At a location which is the inside of the main body 10 and is located on the lower side of the sink 12b, a distribution pipe (not illustrated) imitating a state communicating with a drain ditch portion of the sink 12b is provided on an inner surface side of a rear wall.

The chopping board 20 is a plate member that has a substantially rectangular shape horizontally long in the right and left directions when viewed from the upper side and four corners thereof are R-chamfered (round-chamfered). As illustrated in an enlarged drawing E1 in FIG. 2, a first engaging portion 21a depressed in a recessed shape to the lower side is provided on a portion of the chopping board 20 in which the right-side carrot model 31 is provided. In the first engaging portion 21a, an opening end 21al thereof has a substantially rectangular shape horizontally long in the right and left directions.

On the other hand, a second engaging portion (engaging portion) 22a protruding in a protruding shape to the upper side is provided on a portion of the chopping board 20 in which the left-side carrot model 32 is provided. The second engaging portion 22a protrudes in a substantially rectangular parallelepiped horizontally long in the right and left directions and four corners thereof are formed in an R shape. In the substantially middle portions in the right and left directions of both side surfaces facing in the front and rear directions in the second engaging portion 22a, each recess portion (recess) 22al recessed inwards in an arc shape is provided. Each recess portion 22al is provided in a shape extending in the upper and lower directions from the upper end to the lower end of the second engaging portion 22a.

Next, the carrot model 30 will be described with reference to FIG. 3. In FIG. 3, a lower side oriented to the chopping board 20 in the carrot model 30 is shown on the front side. A first engaged portion 31a protruding downwards in a protruding shape is provided on the lower side of the right-side carrot model 31 included in the carrot model 30. The first engaged portion 31a protrudes in a substantially

rectangular parallelepiped horizontally long in the right and left directions and four corners thereof are formed in an R shape. The first engaged portion 31a has dimensions in the upper and lower directions, the right and left directions, and 5 the front and rear directions so that the first engaged portion 31a fits into the first engaging portion 21a provided in the chopping board 20 with almost no clearance, and thus is fitted in the first engaging portion 21a by protrusion-recess fitting. The first engaged portion 31a is fixed to the first 10 engaging portion 21a by an adhesive or the like in the protrusion-recess fitting state to be unmovable.

A second engaged portion (engaged portion) 32a depressed downwards in a recessed shape is provided on the lower side of the left-side carrot model 32 included in the 15 carrot model 30. An opening end of the second engaged portion 32a is formed in a substantially rectangular shape horizontally long in the right and left directions. Dimensions of the second engaged portion 32a in the upper and lower directions and the front and rear directions substantially 20 match the dimensions in the upper and lower directions and the front and rear directions of the second engaging portion 22a provided in the chopping board 20. On the other hand, a dimension W2 in the right and left directions of the second engaged portion 32a is greater than a dimension W1 in the 25 right and left directions of the second engaging portion 22a. Therefore, the second engaged portion 32a in the protrusion-recess fitting state with the second engaging portion 22a is movable in the right and left directions within a range of the dimension W1 in the right and left directions.

Each protrusion (protrusion) 32al protruding outwards in an arc shape is provided in a portion left close to the front and rear inner surfaces of the second engaged portion 32a. Each protrusion 32al is provided in a shape extending in the upper and lower directions from the opening of the second 30 engaged portion 32a along the bottom surface to correspond to the recess portion 22al of the second engaging portion 22a. The protrusion 32al is locked in the recess portion 22al with almost no clearance.

The right-side carrot model 31 and the left-side carrot 40 model 32 are close in the right and left directions with a slight clearance in the boundary B between the models. An outer edge 31b on a side (left side) of the right-side carrot model 31 close to the left-side carrot model 32 and an outer edge 32b on a side (the right side) of the left-side carrot model 32 close to the right-side carrot model 31 are R-chamfered, respectively. In the embodiment of the present disclosure, the configuration in which the right-side carrot model 31 and the left-side carrot model 32 are close with a slight clearance has been exemplified. However, the “closeness” of the right-side carrot model 31 and the left-side 45 carrot model 32 disclosed in the present specification also includes abutting of the right-side carrot model 31 and the left-side carrot model 32 with each other without any clearance.

Next, an operation mode of an operation in which the left-side carrot model 32 close to the right-side carrot model 31 is separated from the right-side carrot model 31 using the kitchen knife model 40 will be described with reference to FIGS. 4A to 5B. As illustrated in FIGS. 4A and 5A, in the 50 state where the left-side carrot model 32 is closed to the right-side carrot model 31, that is, a state where the shape of the carrot model 30 is formed as a whole, the protrusion 32al of the left-side carrot model 32 is locked in the recess portion 22al of the second engaging portion 22a, and thus the second engaging portion 22a is located on the left end side in the second engaged portion 32a so that both the 55 models are fitted.

Here, as illustrated in FIG. 4A, the user downwards puts down (presses down) the kitchen knife model 40 imitating the shape of a cutter by applying the kitchen knife model 40 to the boundary B of the carrot model 30 from above. Then, since the right-side carrot model 31 is fixed to the chopping board 20, the right outer edge 32b of the left-side carrot model 32 is pressed to the left by the kitchen knife model 40 and the protrusion 32al escapes from the recess portion 22al. Then, the left-side carrot model 32 is moved to the left (a D1 direction illustrated in FIG. 4A) along the second engaging portion 22a. Resistance occurs when the protrusion 32al escapes from the recess portion 22al. Therefore, the resistance can be sensed when the kitchen knife model 40 is put down.

When the left-side carrot model 32 is pressed by the kitchen knife model 40 and moved to the left, the second engaging portion 22a is located to the right end inside the second engaged portion 32a (a state where the left-side carrot model 32 is separated from the right-side carrot model 31, that is, the state illustrated in FIG. 5B). By moving the left-side carrot model 32 to the left, clearance is opened between the left-side carrot model 32 and the right-side carrot model 31 and the kitchen knife model 40 is put down on the chopping board 20, as illustrated in FIG. 4B. Here, since the right outer edge 32b of the left-side carrot model 32 is R-chamfered, the kitchen knife model 40 is smoothly guided downwards along the outer edge 32b.

As described above, in the kitchen toy 1 according to the embodiment of the present disclosure, by putting down the kitchen knife model 40 or the like to the boundary B of the carrot model 30 downwards from the upper side, the outer edge 32b of the left carrot model is pressed by the kitchen knife model 40 and the left-side carrot model 32 is moved to the left. Accordingly, the left-side carrot model 32 is separated from the right-side carrot model 31. Therefore, the user playing with the kitchen toy 1 can feel as if the user cut the carrot model 30 with the kitchen knife model 40, that is, as if the user cooked the carrot model 30, and thus can simply enjoy a play imitating a state change of the carrot model 30 before and after cooking.

According to the foregoing embodiment of the present disclosure, the model toy and the cooking toy according to the following aspects can be provided.

A model toy according to a first aspect includes: a main body including a plate portion; a first figure body provided on the plate portion; and a second figure body provided on the plate portion so as to be arranged in a state where the second figure body is close to the first figure body along an arrangement direction in which the first figure body and the second figure body are arranged. The first figure body engages the plate portion immovably, and the second figure body engages the plate portion movably to allow the second body to move in a direction in which the second figure body is separated from the first figure body along the arrangement direction.

In such configuration, when the outer edge of the second figure body facing the first figure body is pressed in the state where the second figure body is close to the first figure body, the second figure body is moved along the arrangement direction to be separated from the first figure body. For example, the first and second figure bodies are arranged in the arrangement direction and define the whole shape of a cooking object in the state in which the first and second figure bodies are close to each other. Then, when a user puts down a figure body imitating the shape of a cutter to the boundary of the first and second figure bodies downwards from the upper side in the state where the first and second

figure bodies are close to each other, the outer edge of the second figure body is pressed by the cutter-like figure body, and thus the second figure body is separated from the first figure body. Therefore, the user can feel as if the user cuts the cooking object, and thus can simply enjoy a play imitating a state change before and after cooking.

In the model toy according a second aspect, the plate portion includes an engaging portion provided in a portion of the plate portion where the second figure body is provided, the second figure body includes an engaged portion that engages the engaging portion, one of the engaging portion and the engaged portion has a protruding shape, and the other of the engaging portion and the engaged portion has a recessed shape, and dimension of the engaged portion is greater than that of the engaging portion in the arrangement direction.

In such configuration, the engaged portion fitted in the engaging portion by the protrusion-recess fitting can be moved along the arrangement direction. Therefore, it is possible to implement a specific configuration in which the second figure body provided with the engaged portion can be moved along the arrangement direction.

In the model toy according a third aspect, a protrusion is provided in one of the engaging portion and the engaged portion, a recess corresponding to the protrusion is provided in the other of the engaging portion and the engaged portion, the protrusion is locked in the recess in the state where the second figure body is close to the first figure body, and the protrusion escapes from the recess in response to the second figure body being moved along the arrangement direction to be separated from the first figure body.

In such configuration, when the second figure body close to the first figure body is moved in the direction in which the second figure body is separated from the first figure body, the protrusion escapes from the recess. Accordingly, resistance occurs when the protrusion escapes from the recess by pressing the outer edge of the second figure body by the figure body or the like imitating the shape of the cutter, and the resistance creates an illusion of resistance received when a cooking object is cut. Therefore, the user can feel more realistically as if the user cuts the cooking object, and thus can simply enjoy a play imitating a state change before and after cooking.

In the model toy according a fourth aspect, the first figure body is shaped to define a part of a cooking object, and the second figure body is shaped to define a rest of the cooking object to define a whole shape of the cooking object in the state where the second figure body is close to the first figure body.

In such configuration, it is possible to implement a specific configuration of the first and second figure bodies for allowing the user to feel as if the user cuts the cooking object when the second figure body is separated from the first figure body.

A cooking toy according to the first aspect includes: a main body including a plate portion; a first figure body provided on the plate portion and defining a part of a cooking object; a second figure body provided on the plate portion so as to be arranged in a state where the second figure body is close to the first figure body along an arrangement direction in which the first figure body and the second figure body are arranged, the second figure body defining a rest part of the cooking object to define a whole shape of the cooking object when the second figure body is continuous with the first figure body; and a third figure body imitating a shape of a cutter configured to cut the cooking object. The first figure body engages the plate portion

immovably. The second figure body engages the plate portion movably to allow the second figure body to move in a direction in which the second figure body is separated from the first figure body along the arrangement direction when a side of the second figure body facing the first figure body is pressed by the third figure body.

In such configuration, the outer edge of the second figure body facing the first figure body in the state where the second figure body is close to the first figure body is pressed by the third figure body, and the second figure body is moved along the arrangement direction to be separated from the first figure body. Therefore, when the user puts down the third figure body downwards to the boundary of the figure bodies in the state where the second figure body is close to the first figure body, that is, the state where the whole shape of the cooking object is formed, the second figure body is separated from the first figure body. Therefore, the user can feel as if the user cuts the cooking object with the third figure body, and thus can simply enjoy a play imitating a state change before and after cooking.

In the cooking toy according the second aspect, an outer edge of the second figure body facing the first figure body is round-chamfered.

In such configuration, when the user puts down the third figure body downwards from the upper side to the boundary between the first and second figure bodies, the second figure body is pressed to the left by the third figure body along the round-chamfered portion and the third figure body is guided smoothly downwards. Therefore, an operation of separating the second figure body from the first figure body from the state where the second figure body is close to the first figure body can be performed smoothly, and thus the user can simply enjoy a play imitating a state change before and after cooking.

The embodiment of the present disclosure has been described, but the present disclosure is not limited to the foregoing embodiment and can be modified into various forms without departing from the scope of the present disclosure. For example, in the foregoing embodiment, a carrot model imitating a carrot has been exemplified as a figure body which is a cooking object, but the present disclosure is not limited thereto. Any of various figure bodies imitating food can be used. In the foregoing embodiment, the configuration in which the second engaging portion has a protruding shape and the second engaged portion has a recessed shape has been exemplified. But a configuration in which the second engaging portion has a recessed shape and the second engaged portion has a protruding shape may be implemented.

What is claimed is:

1. A model toy comprising:

a main body comprising a plate portion;
a first figure body provided on the plate portion; and
a second figure body provided on the plate portion so as
to be arranged in a state where the second figure body
is close to the first figure body along an arrangement
direction in which the first figure body and the second
figure body are arranged,

wherein the first figure body is provided on the plate
portion at a side of the second figure body on the plate
portion,

wherein the first figure body engages the plate portion
immovably, and

wherein the second figure body engages the plate portion
movably to allow the second body to move in a
horizontal direction in which the second figure body is
separated from the first figure body along the arrangement
direction.

2. The model toy according to claim 1,

wherein the plate portion comprises an engaging portion
provided in a portion of the plate portion where the
second figure body is provided,

wherein the second figure body comprises an engaged
portion that engages the engaging portion,
wherein one of the engaging portion and the engaged
portion has a protruding shape, and the other of the
engaging portion and the engaged portion has a
recessed shape, and

wherein dimension of the engaged portion is greater than
that of the engaging portion in the arrangement direction.

3. The model toy according to claim 2,

wherein a protrusion is provided in one of the engaging
portion and the engaged portion,

wherein a recess corresponding to the protrusion is pro-
vided in the other of the engaging portion and the
engaged portion,

wherein the protrusion is locked in the recess in the state
where the second figure body is close to the first figure
body, and

wherein the protrusion escapes from the recess in
response to the second figure body being moved along
the arrangement direction to be separated from the first
figure body.

4. The model toy according to claim 1,

wherein the first figure body is shaped to define a part of
a cooking object, and

wherein the second figure body is shaped to define a rest
of the cooking object to define a whole shape of the
cooking object in the state where the second figured
body is close to the first figure body.

5. A cooking toy comprising:

a main body comprising a plate portion;
a first figure body provided on the plate portion and
defining a part of a cooking object;
a second figure body provided on the plate portion so as
to be arranged in a state where the second figure body
is close to the first figure body along an arrangement
direction in which the first figure body and the second
figure body are arranged, the second figure body defin-
ing a rest part of the cooking object to define a whole
shape of the cooking object when the second figure
body is continuous with the first figure body; and
a third figure body imitating a shape of a cutter configured
to cut the cooking object,

wherein the first figure body engages the plate portion
immovably, and

wherein the second figure body engages the plate portion
movably to allow the second figure body to move in a
direction in which the second figure body is separated
from the first figure body along the arrangement direc-
tion when a side of the second figure body facing the
first figure body is pressed by the third figure body.

6. The cooking toy according to claim 5,

wherein an outer edge of the second figure body facing the
first figure body is round-chamfered.
